UNITED STATES PATENT OFFICE.

VALENTINE W. HOUCK, OF BUFFALO, NEW YORK.

IMPROVEMENT IN STAVE-DRESSING MACHINES.

Specification forming part of Letters Patent No. 35,681, dated June 24, 1862.

To all whom it may concern:

Be it known that I, VALENTINE W. HOUCK, of the city of Buffalo, county of Erie, and State of New York, have invented certain new and useful Improvements in Stave-Dressing Machines; and I do hereby declare that the following is a full, clear, and exact description of the construction and operation of the same, reference being had to the annexed drawings, making a part of this specification, in which—

Figure I is a side elevation of my improved machine. Fig. II is a plan of the same. Fig. III is a cross-section on line 1 2 of Fig. I. Fig. IV is a longitudinal section.

Letters of like name and kind refer to like parts in each of the figures.

A A', B B', C C', and D D' represent four pairs of feed and pressure rollers, and which are also hereinafter distinguished as the second, third, fourth, and fifth pairs, the guide feed-rollers E E' being the first pair. The upper rollers, A B C D, are concave and the lower rollers, A' B' C' D', are convex. The lower rollers have annular grooves a^2 cut in them, and the fillets between will indent into the stave sufficiently to cause it to feed perfectly straight.

E and E' are guide feed-rollers. They are of greater diameter than the others, and have straight surfaces, the lower one being fluted to increase its hold upon the stave. The upper roller, E, is made in two equal parts and placed upon the shaft so as to leave a space between them in order to admit a guide-stop to project above the periphery, as hereinafter described.

F represents the main frame. It has jaws F' projecting upwardly to hold the journal-boxes b², in which the roller-shafts revolve.

C² are springs placed over the upper boxes to allow the upper rollers to yield for the passage of staves differing in thickness.

d² are screws by which the pressure of the springs may be increased or diminished.

G is the main driving-shaft, having a driving-pulley, G', on one end, with a clutch, e², on the same end, which clutch is operated by the levers e³, e⁴, and e⁵, so that the operator may throw the machine in and out of gear at pleasure.

f² is a pinion on the opposite end of the driving-shaft, which gears with a spur-wheel, g², having also a pinion, g³, on the same shaft. This pinion gears with the large spur-wheel g⁴ upon the end of the shaft of the lower guide feed-rollers.

g⁵ g⁶ g⁷ g⁸ are spur-wheels on the ends of the successive lower feed-roller shafts, being all of the same size.

g⁹ is a spur-wheel which connects the wheel g⁴ with the wheel g⁵, the proportion being such as to give the same surface velocity to all and each of the feed-rollers.

h¹ h² h³ are pinions connecting the spur-wheels g⁵, g⁶, g⁷, and g⁸, and giving the same motion in the same direction to the feed-rollers.

I represents spur-wheels upon the opposite ends of the feed-roller shafts, which gear with each other in pairs and give motion to the upper feed-rollers. They have long teeth to allow for a vertical movement of the upper feed-rollers.

H is a gate in which the jointing-cutters are supported. This gate has a vertical movement on the guides J, which guides are bolted to the main frame between the third and fourth pairs of feed-rollers.

K is a curved bed-plate supported upon the cross-bars K', between the third and fourth pairs of feed-rollers. Its longitudinal curve is that of the bilge of the barrel, and its transverse curve is an arc of the circumference of the barrel at its bilge, (for which the staves are being jointed,) or nearly so. It is fluted exactly in line with the lower feed-rollers, so that the stave will pass in a direct line and be held to the action of the jointers without any side slip.

L represents a former-plate, of which there is one for each different width of stave, its under side being hollowed out to the exact curvature the stave is to have in the barrel. This plate is bolted to the bars l', which bars have an eye in each of their ends, through which eyes four bolts, l'', projecting upwardly from the cross-bars K', pass. Spiral springs l''' are placed around these bolts, bearing upon the ends of the bars l' and the nuts on the bolts, so as to give a yielding pressure to

the former-plate to accommodate different thicknesses of staves. The stave passes between the bed-plate and the former, and is held by them for the action of the cutters.

M represents the jointing cutter-heads, one on each side of the former and bed-plate.

m^2 are cutter-head shafts, which have journal-bearings in the boxes m^3 , above and below. The upper and lower boxes are connected by arms m^4 , which bend outwardly to give room for the revolution of the cutters. Flat arms m^5 (strengthened by a feather) project downwardly from the lower boxes and are hinged by bolts m^6 to the lower cross-piece of the gate near its center, so that the cutting-edges of the knives will point to (or nearly so) the supposed center of the barrel.

The upper journal-boxes are connected and held firmly to the gate by bolts n' , which pass through curved slots n^2 in the upper cross-piece of the gate, (the centers from which the slots are described being the centers of the bolts m^6 .) By means of the adjusting-screws n^3 the angle of the cutters may be changed (the bolts n' being first loosened) for different widths of staves, their cutting-edges always pointing to the supposed center of the barrel, (or nearly so,) and thereby giving the proper bevel to the stave. The gate (and with it the cutters) has an up-and-down vertical movement equal to half the bilge of the barrel, or the difference between the radius of the end and the radius of the center of the barrel, which movement is given by means hereinafter described. The length of the knives (or cutters) is somewhat greater than their vertical movement, and their position upon their shafts is such that their lower ends will never pass above, nor their upper ends below, the stave which is being jointed.

n^4 are driving-pulleys on the cutter-shafts.

O is a rock-shaft supported by the hangers O', which are bolted to the main frame.

O² is an arm held by a set-screw.

O³ is a short connecting-rod, which connects the end of the arm with the center of the bottom cross-piece of the gate.

P is a cam supported on end of shaft, which shaft has a central support on the main frame. This cam is constructed as follows: Two lines at right angles to each other are drawn through the center of the cam. The longest radius of the cam is assumed of any convenient length and laid off on each side of the center upon one of these lines. The shortest radius of the cam is as much less as the required throw of the jointing-cutters, which, as before stated, is the difference between the longest and shortest radius of the barrel, and this radius is laid off on the other line. Two circular arcs are now drawn, (by a well-known problem,) each passing through one of the last-obtained points and through both of the points first obtained. This will give the form of the cam.

P' is a horizontal bar connected at one end to the arm P², at right angles to the arm O², and

supported at the other end by a vibrating rod p³. It has a friction-wheel, p⁴, in this end against which the cam revolves. The motion of the cam is thus transmitted to the gate, and hence to the cutters, through the bar P', arm P², rock-shaft O, arm O², and connecting-rod O³. The arm P² is slotted, so that the length of its leverage may be varied, and consequently the rise and fall of the cutters varied for different bilges of staves. It is evident from the form of the cam that it will give two up and two down motions to the gate and cutters at each revolution which it makes. The weight of the gate and cutters will keep the friction-wheel in contact with the cam during the descent of the gate and cutters.

The object of the combination of the cam with the rock-shaft and levers, as described, is to carry the cutters so quickly past the transition-point (which transition-point is when the cutters are at the center of the stave) as to joint the bilge of the stave on a true curve. In other machines the transition-point is so slow that the stave will have a forward movement of an inch or more while the cutters pass the transition-point, and hence there will be a straight surface of an inch or more on the bilge curve of the stave. This is a serious objection, and to avoid this objection the cam is made of peculiar shape and put into said combination. It accomplishes the object in an admirable manner. It carries the cutters past the transition-point instantly and makes the bilge on a true curve. This combination is also adjustable, so as to easily adapt the cutters to jointing staves for different bilges of barrels.

Motion is given to the cam as follows: A pinion, q, is placed upon the lower guide feed-roller shaft, and a spur-wheel, q', upon the end of the cam-shaft, and a connecting-pinion, q², communicates the motion of the guide feed-rollers to the cam.

When the machine is set for jointing staves of any given length, it is evident that the gate and cutters must have one up and one down movement while the stave is fed forward its length, and as each revolution of the cam gives two of these movements the connecting-pinion q² must be of such size as to allow the feed-rollers to move the stave forward its whole length in exact time with one up and one down movement of the jointing-cutters. The pinion q² is so supported upon the slotted arm q³ that it may be removed at pleasure and another pinion used in its place, so that by substituting a pinion of the required size the vertical movement of the gate and jointing-cutters may be timed exactly to correspond with the feed movement of the stave, and hence the machine is adapted to dressing staves of any required length. The cutters are set upon an angle corresponding to the required bevel of the stave, and the rise and fall of the jointing-cutters while jointing the stave will give the required bilge and taper, because

as the cutters fall the distance between that part of them which is cutting will increase on account of the angle upon which they stand, and as they rise the distance will diminish. The longitudinal movement of the stave through the machine and the vertical movement of the gate and cutters are so regulated in relation to each other as to give the proper shape to the stave, no matter what its length may be.

R is a cutter-head for planing the outside surface of the stave, and R' is a pulley for driving the same. It is located between the first and second pairs of feed-roller.

r² represents small pressure-rollers, one on each side of the cutter-head, for holding the stave to the action of the cutters. The second, third, fourth, and fifth pairs of feed-rollers are placed upon a curve of decreasing radius, so that the stave will be gradually bent in its passage between them to the curve it is to assume in the barrel, sufficient allowance being made for what the stave will spring back after passing from the machine. The concavity and convexity of these rollers increase correspondingly for the purpose of giving the proper transverse curve to the stave. By these means the liability of splitting or breaking the stave in bending it to its required form is avoided.

It is essential to the making of a perfect stave that it should be fed to the jointing-cutters at such time that the center of the stave will reach the cutters at the moment they are at their lowest position, and consequently the ends of the stave will be jointed while the cutters are in their highest position, and the gradual rise and fall of the cutters will give the proper taper or bilge of the stave. It is also essential that the stave should be so fed to the machine that its longitudinal center line will follow the longitudinal center line of the machine, bisecting the distance between the jointing-cutters. For this purpose I arrange upon the feed-table T a side guide-piece, U, which has a curvature corresponding to the curvature of the edge of the stave when "listed." The listed staves are assorted according to their different widths, and the jointing-cutters are set for running through a lot of a certain width. The guide-piece U is connected at one end by a bolt, u', to an arm, u², which arm is secured to the feed-table T by a bolt, u³, passing through the slot u' in the table. To the opposite end of the guide-piece is connected a rod, v, which passes through an eye, v', which projects up from the table. An arm, v², is connected to this rod by a set-screw, v³, and a spring, v⁴, which, pressing against the arm and the eye v', will press the guide-piece toward the center of the machine, it turning upon the bolt u' at the opposite end. This guide-piece is set by moving the arm u² in the slot and the arm v² on the rod, so that when the listed stave is laid against it its center will correspond to the center line of the

machine. A cam, W, is connected to the side of the feed-roller, which, as the feed-roller revolves and draws the stave in, will strike the arm v² and draw the guide away, so as to allow the center of the listed stave (which is wider at the middle than it is at the ends) to pass the point of the guide-piece and hold until the stave passes. The spring v⁴ will then force the guide back into place for the next stave. This guide-piece and the guide-stop insure the proper feeding of the stave to the machine.

A listed stave is one which has had its edges clipped by a pair of shears or cutters in its bilge or taper form.

In order to insure accuracy in the delivery of the stave to the jointing-cutters at the proper time and motion, and in order to easily adapt the machine to jointing staves of different lengths, I have constructed the following device, which is easy of adjustment and accurate in its operations: The upper guide feed-roller, E, is made in two equal parts, and these parts are so placed upon the shaft as to leave a narrow space between them upon this shaft, and between the two parts of the said roller I place a guide-stop, S. It is so constructed that it may be turned round on the shaft, and by means of the set-screw S' it may be fixed to the shaft, as desired. Within its main body is placed a coil-spring, S², and stop-bar S³, the bar resting upon the spring in such a manner that it may be thrown outwardly by the spring, so that it will project slightly above the periphery of the roller and form a guide-stop, against which the end of the stave is placed when it is fed into the machine. The object of making this stop yielding (by means of the spring S²) is to adapt the machine to jointing staves of greater length than the circumference of the guide feed-rollers, and so that by using two or more of these stops staves which are shorter than the circumference of the said feed-rollers may be fed in without loss of motion. When two or more of these guide-stops are used for short staves, those of them which are not used for the stave which is passing in may, as they come round, strike upon the surface of the stave without injury. The spring S² will yield and allow the stop to slide up and pass over the surface without marring the stave; and so, also, when a stave is jointed which is longer than the circumference of the guide feed-roller, as the stop against which it was placed comes around and strikes upon the surface of the stave which has not yet passed through the feed-rollers it will yield and allow the stave to pass along without injury.

What I claim as my invention, and desire to secure by Letters Patent, is—

1. The adjustable and yielding guide-stop S, in combination with the guide feed-rollers E, E', for the purposes and substantially as described.

2. The yielding guide-piece U, in combina-

tion with the cam W, for the purposes and substantially as set forth.

3. The cam P, in combination with the bar P', arm P², friction-wheel p⁴, and vibrating rod p⁵ and rock-shaft O, for the purposes and substantially as set forth.

4. The curved bed-plate K, having flutes

exactly corresponding to and placed in line with those of the lower feed-rollers, for the purposes and substantially as described.
